UNITED STATES PATENT OFFICE.

WILLIAM H. THOEMING, OF DETROIT, MICHIGAN, ASSIGNOR TO VANGUARD MANUFACTURING COMPANY, OF DETROIT, MICHIGAN, A CORPORATION OF ILLINOIS.

DESIGN FOR TUBING FOR WIND-SHIELD FRAMES.

47,868.

Specification for Design.

Patented Sept. 21, 1915.

Application filed April 11, 1913. Serial No. 760,553. Term of patent 7 years.

To all whom it may concern:

Be it known that I, WILLIAM H. THOEMING, a citizen of the United States, and a resident of Detroit, in the county of Wayne and State of Michigan, have invented a new and original ornamental Design for Tubing for Wind-Shield Frames, of which the following is a specification, reference being had to the accompanying drawings, forming a part hereof.

Figure 1 is a side elevation of tubing for wind shield frames, showing my new design; Fig. 2 is a top plan view of the tubing; Fig.

3 is a bottom plan view of the tubing; and Fig. 4 is a cross-sectional view of the tubing showing the external form thereof.

I claim:

The ornamental design for tubing for wind shield frames.

In testimony whereof, I have hereunto set my hand, this 7th day of April, 1913, in the presence of two subscribing witnesses.

WILLIAM H. THOEMING.
